SALVAGING DEVICE

Joseph Wertheimer, Far Rockaway, N. Y.

Application June 5, 1944, Serial No. 538,787

3 Claims. (Cl. 114—51)

This invention relates to improvements in apparatus or devices for salvaging sinking water craft or vessels.

It is an object of the present invention to provide two parallelly-disposed ships or vessels held in fixed position in relation to each other for salvaging purposes.

It is another object of the present invention to provide such vessels with a plurality of hoisting means which may operate either separately or together in unison as a unit.

A further object of the present invention is to provide two vessels held in fixed relation to each other and equipped with hoisting means including cables, to which cables is attached a net forming a cradle adapted to be manipulated under a sinking ship or water craft to prevent the same from sinking and to salvage the same.

Yet another object of the present invention is to provide said salvaging vessel with pumping and towing equipment used during the salvaging operation.

These and other objects of the invention are accomplished by the novel and practical construction, combination and arrangement of parts hereinafter disclosed and illustrated in the accompanying drawings, constituting an essential part of the disclosure, and in which:

Fig. 1 is a side-elevational view of ship salvaging apparatus embodying the invention;

Fig. 2 is a left-hand end view of Fig. 1, showing one of the vessels in section; and

Fig. 3 is a top plan view of Figs. 1 and 2.

Referring now more particularly to the drawings, there is disclosed a pair of vessels 10 and 11, held in spaced-apart fixed parallel relation by means of a plurality of spaced girders 12 preferably of channel construction.

As is clearly seen in Fig. 2, the girders are arranged transversely of and encircles the sides and bottom of the ships 10, 11; each girder forming in shape a double U at the top, one U 13 within the other U 14, and a pair of U's 15, 16, at the lower ends of the girder. In other words, the outer sides of the U's 15, 16 are connected together by the side of the outer U indicated by the numeral 14, whereas, the inner sides of the U's 15, 16 are connected together by the sides of the inner U indicated by the numeral 13, making a firm, sturdy solid construction binding together the vessels 10 and 11 in fixed parallel relation.

Arranged along the length of the vessels 10, 11, are a plurality of derricks 17 having their fixed booms or beams 18 angularly disposed, the ends of the booms of the derricks on each vessel pro-

jecting over a side thereof and into the space 20 between the vessels. The booms 18 are provided with pulleys 21, over which are trained the cables 22, one of the ends of which are connected to 5 hoisting mechanisms (not shown) located at convenient points in the vessels. These derricks may be so arranged as to be operated separately or simultaneously as a unit.

Attached to the depending ends 23 of the cables 22 is a net 24 being of any required mesh and being made of suitable material, by which a cradle 25, particularly for salvaging purposes.

At the ends of the vessels 10, 11, there may be 15 provided further derricks 26 having swinging booms or beams 27, which may be employed for raising or supporting a portion of a sinking ship while the net is being adjusted therebeneath. Beam 27 will be provided with the usual pulley 28, cable 29 and hook 30 secured to the end of the latter.

The vessels may be provided with the customary smokestacks 31, masts 32, decks 33, 33a, 33b, 33c, loading holes 40, etc. and bridge 34.

25 Reinforcing members 5, 36 connect together the overhanging portions 37, 38, of the girders.

From the foregoing description, it is evident that there has been provided by this invention practical, efficient and economical means for retrieving and salvaging vessels.

Although the drawings, and the above specification disclose the best mode in which I have contemplated embodying my invention, I desire in no way to be limited to the details of such disclosure, for in the further practical application of my invention many changes in the forms and proportions may be made as circumstances require or experience suggests without departing from the spirit of the invention within the scope 40 of the appended claims.

Having thus described my invention what I claim as new and desire to secure by Letters Patent, is:

1. Salvaging apparatus comprising a pair of vessels, means maintaining said vessels in fixed spaced relation, said means comprising a plurality of girders, each of said girders including U-shaped portions, one within the other, and other U-shaped portions enveloping the sides and bottom of said vessels, respectively, said other portions being connected to said first-named portions, and means connected to said vessels for supporting water craft between said vessels.

2. Salvaging apparatus comprising a pair of vessels, means maintaining said vessels in fixed

spaced relation, said means comprising a plurality of girders, each of said girders including U-shaped portions, one within the other, and other U-shaped portions enveloping the sides and bottom of said vessels, respectively, said other portions being connected to said first-named portions, and means connected to said vessels for supporting water craft between said vessels, said supporting means comprising a plurality of derricks on said vessels, a net disposed between said vessels, said derricks having flexible means connectable with said net.

5

10

3. Salvaging apparatus comprising a pair of vessels, means maintaining said vessels in fixed spaced relation with respect to each other, means for supporting water craft between said vessels; said means comprising a cradle disposed between said vessels; means for supporting said cradle between said vessels, means for operating said supporting means whereby said cradle may be raised and lowered, selectively, and means for raising a portion of said water craft for facilitating placement of said cradle beneath said water craft.

JOSEPH WERTHEIMER.
